Patented February 7, 1905.

UNITED STATES PATENT OFFICE.

JOHN R. WILLIAMS, JR., OF WEST ORANGE, NEW JERSEY.

SELF-LUBRICATING PULLEY-WHEEL.

SPECIFICATION forming part of Letters Patent No. 781,799, dated February 7, 1905.

Application filed November 25, 1904. Serial No. 234,120.

To all whom it may concern:

Be it known that I, JOHN R. WILLIAMS, Jr., a citizen of the United States, and a resident of West Orange, in the county of Essex and State of New Jersey, have invented certain new and useful Improvements in Self-Lubricating Pulley-Wheels and the Like, of which the following is a specification.

The invention relates to improvements in self-lubricating pulley-wheels and the like; and it consists in the novel features and combinations of parts hereinafter described and claimed.

The object of the invention is to produce a hub construction adapted to form a reservoir for the lubricant and which will assure the maintenance of a proper body of oil at the bearing-surface of said hub.

One of the essential objects of my invention is to overcome the general objection to self-oiling wheels—that the centrifugal action carries the oil to the outer portions of the reservoir and the bearing-surfaces are insufficiently lubricated; and in carrying out my invention I provide within the chambered hub of the wheel stationary means which in part prevent the oil from being to an undue extent thrown outwardly during the rotation of the wheel and which feed the oil from the upper side of the chamber to the bearing-surfaces of the hub. The oil which passes to the shaft on which the wheel is loosely mounted travels between the same and the bearing-surfaces of the hub and returns through suitable apertures or inlet-ports in the hub to the reservoir to be used over again in lubricating said surfaces; whereby I not only feed oil to said surfaces, but maintain a suitable supply of the same therat.

The invention will be fully understood from the detailed description hereinafter presented, reference being had to the accompanying drawings, in which—

Figure 1 is a central vertical longitudinal section, partly broken away, of a pulley-wheel constructed in accordance with and embodying the invention, the section being on the dotted line 1-1 of Fig. 2. Fig. 2 is a central vertical transverse section of same on the dotted line 2-2 of Fig. 1, and Fig. 3 is a de-

tached top view of the means I provide within the hub to control the centrifugal throw of the oil and feed the oil to the bearing-surfaces.

In the drawings, 10 designates a pulley-wheel loose upon a shaft 11, said wheel being composed of two corresponding parts 12 13, fitted and secured together by an annular tongue and groove 14 and screws or bolts 15. The wheel parts 12 13 have hub-sections 16 17, beyond which within the hub portion of the wheel is formed a chamber or reservoir 18 for the oil, said chamber being of adequate capacity in accordance with the size of the wheel and one wall of which being supplied with a filling-orifice 19, adapted to be closed by a plug 20.

The hub-sections 16 17 have within their outer edges the annular grooves 21, from which return-ports 22 lead to the chamber or reservoir 18, and the said sections 16 17 are separated from each other at their inner edges and receive freely between them the eccentrically-shaped weight or pendent body 23, which has hub-flanges 24, loosely fitting upon the inner portions of the hub-sections 16 17. The body 23 extends below the shaft 11 to nearly the outer edge of the chamber 18, while above said shaft said body terminates at its hub-flanges 24 and is there provided with a series of vertical apertures 25, open at both ends and leading to the shaft 11, and the central one of which apertures is in communication with a conduit 26, which is in the form of a tube having openings in its sides and which I prefer to form of wire coiled in the manner of a spring. The conduit 26 extends upwardly to a point in near relation to the outer edge of the chamber 18.

In the employment of the invention a suitable quantity of the oil is supplied to the chamber or reservoir 18, and thereafter when the wheel is set in motion the pendent body 23 will remain stationary, or substantially so, and the oil will be carried around by the walls of the chamber 18 and centrifugal action. The oil carried above the shaft 11 will be partly intercepted on its passage by the conduit 26, which standing in the path of the oil will be struck by the same, with the re-

sult that a part of the oil will enter between the coils of said conduit and descend through the latter to the central aperture 25 and thence reach the shaft 11. Other portions of the oil intercepted by the conduit 26, but not entering and descending through the same, will fall upon the upper end of the body 23 and pass through the exposed apertures 25 to the shaft 11. The oil which passes through 10 the conduit 26 and apertures 25 will travel along the shaft 11 and inner surfaces of the hub-sections 16 17 and finally reach the grooves 21, whence, due to centrifugal action, it will pass through the ports 22 and return to the reservoir 18. Thus there will during the use of the wheel be a constant circulation of the oil from the reservoir through the apertures 25 and conduit 26 to the shaft 11, thence along said shaft to the annular grooves 21, and thence through the return-ports 22 to said reservoir.

The pendent weighted body 23 maintains the conduit 26 substantially vertical and stationary during the rotation of the wheel, and 25 the downwardly-extending portion of said body aids in preventing undue centrifugal action of the oil within the chamber or reservoir 18, said portion of said body being suspended in the path of the oil and breaking 30 the momentum of the latter during the use of the wheel, but not interfering with a sufficient quantity of said oil being carried upwardly over the shaft 11 to supply the conduit 26.

35. The invention is not limited to the employment of any special outline of weighted body 23, although I prefer the eccentric arrangement of body shown, nor is the invention limited to the employment of the series of apertures 25, since these apertures may be increased or reduced in number, nor is the invention limited to the formation of the conduit 26 from the rod of wire spirally coiled, since the conduit 26 is primarily a tube having 40 openings to receive the oil carried upwardly over the shaft, so that the conduit may conduct such oil as may pass within it to said shaft. When, however, the conduit 26 is made in the form of a spiral coil, it is very light and 45 sensitive and answers all the purposes of a metal tube having slits or apertures formed in its sides and presents surfaces to the moving oil which are sufficiently irregular to arrest and break up the oil, whereas the smooth 50 surfaces of a tube might serve to simply deflect the larger portion of the oil without properly arresting a sufficient quantity thereof for lubricating the shaft 11. The lower end of the conduit 26 is fastened in the upper 55 end of the central aperture 25.

What I claim as my invention, and desire to secure by Letters Patent, is—

1. A wheel having a chambered hub portion to receive the lubricant and being in communication with the shaft, said hub portion also

having return-ports to said chamber, combined with the weighted body suspended within said chamber from about said shaft and having at its upper side an upwardly-extending conduit having openings to receive the 70 oil, said conduit standing in the path of the oil carried around by centrifugal action and leading to said shaft; substantially as set forth.

2. A wheel formed of sections secured together and forming the interior chamber to 75 receive the lubricant and also the bearing-hub to engage the shaft, said hub being in sections separated at their inner ends from each other, and said hub having the return-ports for the lubricant, combined with the weighted body 80 suspended from about said shaft and within said chamber, and a conduit at the upper side of said body leading to said shaft, said conduit standing in the path of the oil carried around by centrifugal action and having openings through which the oil may pass into the conduit; substantially as set forth.

3. A wheel having a chambered hub portion to receive the lubricant and being in communication with the shaft, said hub portion also 90 having return-ports to said chamber, combined with the weighted body suspended within said chamber from about said shaft and having at its upper side an upwardly-extending conduit having openings to receive the 95 oil, said conduit standing in the path of the oil carried around by centrifugal action and leading to said shaft and consisting of a coiled-wire tube; substantially as set forth.

4. A wheel having a chambered hub portion 100 to receive the lubricant and being in communication with the shaft, said hub portion also having return-ports to said chamber, combined with the weighted body suspended within said chamber from about said shaft and 105 having at its upper side an upwardly-extending conduit having openings to receive the oil, said conduit standing in the path of the oil carried around by centrifugal action and leading to said shaft, and said body containing, at its upper side, apertures leading to said shaft; substantially as set forth.

5. A wheel having a chambered hub portion to receive the lubricant and being in communication with the shaft, said hub portion also 115 having return-ports to said chamber, combined with the weighted body suspended within said chamber from about said shaft and having at its upper side an upwardly-extending conduit having openings to receive the 120 oil, said conduit standing in the path of the oil carried around by centrifugal action and leading to said shaft, and said body being in the form of an eccentric extending downwardly into the chamber below said shaft; substantially as set forth.

6. A wheel formed of sections secured together and forming the interior chamber to receive the lubricant and also the bearing-hub to engage the shaft, said hub being in sections 130

separated at their inner ends from each other, and said hub having the return-ports for the lubricant, combined with the weighted body suspended from about said shaft and within 5 said chamber, and a conduit at the upper side of said body leading to said shaft, said conduit standing in the path of the oil carried around by centrifugal action and serving to arrest a part of said oil and direct it to said 10 shaft; substantially as set forth.

7. A wheel formed of sections secured together and forming the interior chamber to receive the lubricant and also the bearing-hub to engage the shaft, said hub being in sections 15 separated at their inner ends from each other, and said hub having the return-ports for the lubricant, combined with the weighted body suspended from about said shaft and within 20 said chamber, and a conduit at the upper side of said body leading to said shaft, said conduit standing in the path of the oil carried around by centrifugal action and serving to arrest a part of said oil and direct it to said 25 shaft, and said body containing at its upper side, apertures leading to said shaft; substantially as set forth.

8. A wheel formed of sections secured together and forming the interior chamber to receive the lubricant and also the bearing-hub 30 to engage the shaft, said hub being in sections separated at their inner ends from each other, and said hub having the return-ports for the lubricant, combined with the weighted body 35 suspended from about said shaft and within 40 said chamber, and a conduit at the upper side of said body leading to said shaft, said conduit standing in the path of the oil carried around by centrifugal action and serving to arrest a part of said oil and direct it to said shaft, and said body being in the form of an eccentric and having hub-flanges to engage 45 said hub-sections; substantially as set forth.

9. A wheel formed of sections secured together and forming the interior chamber to receive the lubricant and also the bearing-hub 45 to engage the shaft, said hub being open within said chamber to admit the lubricant to the shaft and also having the return-ports for the lubricant to said chamber, combined with the body freely suspended from about said shaft 50 within said chamber and weighted at its lower side so that it may not rotate with said wheel, while at its upper side said body is open to permit the passage of the lubricant to said shaft, and an upwardly-extending part secured 55 to said body and standing in the path of the oil carried around by centrifugal force and serving to arrest a part of said oil and effect its descent and passage to said shaft; substantially 60 as set forth.

10. A wheel formed of sections secured together and forming the interior chamber to receive the lubricant and also the bearing-hub to engage the shaft, said hub being open within said chamber to admit the lubricant to the 65 shaft and also having the return-ports for the lubricant to said chamber, combined with the upwardly-extending conduit adapted to receive the oil and arranged within said chamber and standing in the path of the oil carried 70 around by centrifugal force and serving to arrest a part of said oil and effect its descent and passage to said shaft, and means for sustaining said conduit within said chamber and preventing its rotation with said wheel; 75 substantially as set forth.

Signed at New York city, in the county of New York and State of New York, this 22d day of November, A. D. 1904.
